UNITED STATES PATENT OFFICE

158,736

LIGHTER THAN AIR AIRSHIP

James D. Frank, Denver, Colo.

Application February 7, 1949, Serial No. 720

Term of patent 3½ years

(Cl. D71—1)

To all whom it may concern:

Be it known that I, James D. Frank, a citizen of the United States, residing in the city and county of Denver, and State of Colorado, have invented a new, original, and ornamental Design for Lighter Than Air Airships, of which the following is a specification, reference being had to the accompanying drawing, forming part thereof.

In the drawing:

Figure 1 is a top plan view of a lighter than air airship, showing my new design;
Figure 2 is a side elevation thereof;
Figure 3 is a front elevation; and
Figure 4 is a bottom plan view looking upwardly in Figure 2.

I claim:

The ornamental design for a lighter than air airship, as shown.

JAMES D. FRANK.
